(57) **CLAIM**

We claim the ornamental design for a film dispensing tool for stationery, as shown and described.

DESCRIPTION

FIG. 1 is a front view of the film dispensing tool for stationery showing our new design, the design having transparent section as illustrated in FIG. 15;

FIG. 2 is a rear view thereof;

FIG. 3 is a left side view thereof;

FIG. 4 is a right side view thereof;

FIG. 5 is a top view thereof;

FIG. 6 is a bottom view thereof;

FIG. 7 is a front perspective view thereof;

FIG. 8 is a front view thereof with a tip of the film dispensing tool in a retracted position;

FIG. 9 is a rear view thereof;

FIG. 10 is a left side view thereof;

FIG. 11 is a right side view thereof;

FIG. 12 is a top view thereof;

FIG. 13 is a bottom view thereof;

FIG. 14 is a front perspective view thereof; and,

FIG. 15 is a front perspective view of the film dispensing tool of FIG. 1 showing transparent sections with grey shading.
